UNITED STATES PATENT OFFICE.

GEORGE A. LEAVITT, JR., OF NEWBURG, NEW YORK.

AUTOMATIC DAMPER.

SPECIFICATION forming part of Letters Patent No. 268,696, dated December 5, 1882.

Application filed April 24, 1882. (No model.)

To all whom it may concern:

Be it known that I, GEORGE A. LEAVITT, Jr., of Newburg, in the county of Orange and State New York, have invented certain new and useful Improvements in Automatic Dampers, of which the following is a full, clear, and exact description.

Reference is to be had to the accompanying drawings, forming a part of this specification, in which similar letters of reference indicate corresponding parts in all the figures.

Figure 1 represents a front end view of an air-current deflecting or directing device constructed in accordance with my invention. Fig. 2 is a horizontal section of the same on the line *x x'* in Fig. 1, and showing the device applied to the cold-air box of a furnace or duct connected therewith; and Fig. 3 is a transverse vertical section of the same on the line *y y'*, in Fig. 2, looking toward the front end of the ventilating device.

My invention relates to improvements in automatic dampers; and it consists in the peculiar construction and arrangement of parts, as hereinafter fully set forth.

A indicates an oblong case or frame, open at its opposite ends and sides, but closed at its top *a* and bottom *b*.

B indicates the cold-air box of a furnace or flue leading thereto.

Hinged to the forward ends of the frame A, as at *c c'*, are long swinging valves D D, opening inward, and forming when closed covers or doors on the opposite open sides of the frame A. These valves, which are designed to be operated by the wind, should be as light as is consistent with requisite strength—the lighter the better—and are each provided on their inner faces with a guard or arm, *d*, having on its outer end a roller, *e*, which is preferably made of rubber, to cushion the blow caused by contact of one door with the other and muffle the sound, either door or valve, as it is opened inwardly, serving to close the other door or valve by means of the guards *d* or attached rollers *e*.

Rubber or other soft cushions *ff* are also provided on opposite sides of the back end of the frame A, for either door to slam against,

and so deaden the noise of its closing, as well as to prevent injury or breakage. The valve, 50 air-box, or frame thus constructed is arranged outside of the house or building, or wherever the supply of cold air is to be drawn from, and with its rear end in communication with the cold-air flue or box of the furnace. Whenever the wind blows from the direction in which the forward end of the frame A fronts, then a direct course will be established for the current through said frame or box, and both valves or doors D D will be closed against 60 their respective sides; but whenever the wind blows from other points of the compass, which will cause it to bear either squarely or obliquely against either door or valve D, such door will be opened inward and the opposite 65 door or valve, if open, will be closed by the opening one, thus deflecting the current and directing it, by the oblique position which the open door or valve assumes, into the cold-air box or flue. In this way a supply of pure or 70 fresh air may be maintained and outward suction of the hot air by crossing or contrary currents may be prevented.

Having thus described my invention, I claim as new and desire to secure by Letters Patent— 75

1. The combination, with the box A, leading into the cold-air box B, and having open sides and ends and closed top and bottom, of the swinging valves D D, opening inward, and pivoted to the frame at *c*, and provided with 80 the arms A, whereby currents of air entering the outer end of the box will close both valves and pass directly into the cold-air box, substantially as described.

2. The combination, with the box A, leading 85 into the cold-air box B, and having open sides and ends and closed top and bottom, of the swinging valves D D, opening inward, and provided with the arms *d d*, having rollers *e e* on their ends, and the cushions *f f*, substantially as and for the purpose set forth. 90

GEORGE A. LEAVITT, JR.
